(57) CLAIM

I claim the ornamental design for a self-defense item, as shown and described.

DESCRIPTION

FIG. 1 is an isometric view of a self-defense item showing my new design;

FIG. 2 is an enlarged front view thereof;

FIG. 3 is an enlarged rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is an enlarged view of a blade of the self-defense item showing a flexible sheath.
The broken lines of FIGS. 1-8 are included for the purpose of illustrating portions of the device that form no part of the claimed design.
